(57) **CLAIM**

The ornamental design for a crown shaped carabiner, as shown and described.

DESCRIPTION

FIG. 1 is a top plan view of my new design for a crown shaped carabiner, it being understood that the bottom view is identical;

FIG. 2 is a front elevational view of the crown shaped carabiner shown in FIG. 1;

FIG. 3 is a rear elevational view of the crown shaped carabiner shown in FIG. 1;

FIG. 4 is a right side elevational view of the crown shaped carabiner shown in FIG. 1, the left side view being identical; and,

FIG. 5 is a top perspective view of the crown shaped carabiner shown in FIG. 1.
